(57) **CLAIM**

The ornamental design for a sandal, as shown and described.

DESCRIPTION

1. Sandal
- 1.1 : Perspective
- 1.2 : Front
- 1.3 : Back
- 1.4 : Right
- 1.5 : Left
- 1.6 : Top
- 1.7 : Bottom

The sandal comprises a low-heeled sole and an upper with two flexible cross-over wings that extend from the edges of the sole; the wing extending from the inner edge of the sole is partially superimposed on the other wing; a respective belt is partially sewn on each of the said wings and the ends of these belts are locked, on the central part of the top, by a clasp comprising a ring-shaped locking element; the shoe shown in the images is a right shoe for use with a symmetrical left shoe.
